Gegrator Corporation, Manassas, Va.

Filed Nov. 2, 1971, Ser. No. 195,067

Term of patent 14 years

Int. Cl. D24—01; D12—14
U.S. Cl. D83—1 H

FIG. 1

FIG. 2

FIG. 4

FIG. 3

FIG. 1 is a perspective view of a table embodying my new design;

FIG. 2 is a top plan view of the table of FIG. 1;

FIG. 3 is a side elevational view of the table of FIG. 1 as seen from the far side of FIG. 1; and

FIG. 4 is an elevational view as seen from the left end of FIG. 2.

The area between the wheel supporting end pedestals and beneath the spanning table structure is free of obstructions providing a totally clear space behind the dependent X-ray protective aprons for positioning X-ray equipment.

I claim:

The ornamental design for a cardiac X-ray table, substantially as shown and described.
